UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A RUG.

SPECIFICATION forming part of Design No. 35,633, dated January 28, 1902.

Application filed December 31, 1901. Serial No. 87,972. Term of patent 3½ years.

To all whom it may concern:

Be it known that I, ADOLPH PETZOLD, a citizen of the United States, residing at Philadelphia, Pennsylvania, have invented and produced a certain new and original Design for a Rug, of which the following is a full, clear, and exact description, reference being had to the accompanying drawing, forming a part of this specification.

10 My invention relates to the surface ornamentation of woven rugs; and it consists of the design therefor shown in said drawing. In its essentials it consists of opposite parallel straight-line figures *a* and *b*, which, however, do not meet, and hence leave open corner-spaces at the four corners of the concrete design. Each of these four corners is filled by a small floral figure *c*, extending into the

field center. The latter contains a central oval frame-like figure *d*, at each end of which 20 is a large bunch of roses *e*, and within its center a bunch of other flowers *f*. Outside the central oval figure and within the outside border the field is covered with a series of small figures *h*. 25

I claim—

The design for a rug substantially as shown and described.

In testimony whereof I have hereunto affixed my signature this 4th day of December, 30 A. D. 1901.

ADOLPH PETZOLD.
